UNITED STATES PATENT OFFICE.

JAY DARLING, OF WILLIAMSPORT, INDIANA.

MACHINE FOR STAMPING OUT MOLDS.

Application filed May 31, 1927. Serial No. 195,531.

The object of my invention is to provide a novel machine for pressing or stamping out molds of thin sheet metal. I attain the objects of my invention by the device illustrated 5 in the accompanying drawings, in which

Figure 1 is a perspective view of my machine;

Fig. 2 is an end elevation of same with a sheet of metal inserted ready to be pressed 10 into the desired shape for use as a mold;

Fig. 3 is an end elevation of the machine in the position it occupies at the conclusion 15 of the pressing operation; and

Fig. 4 is a perspective view of the completed mold.

Like numerals indicate like parts in each of the several views.

Referring to the accompanying drawings, I provide a suitable bottom base block 1 having 20 a tapering approximately semi-cylindrical upstanding form extending longitudinally of the central portion of the base 1 over which the sheet of metal 9 is pressed to form the mold desired. I provide upper blocks 25 3 and 5 of similar shape and having recessed portion 7 corresponding in shape with the tapering upstanding mold form 2 and adapted to seat thereover. I provide a suitable number of hinges 4 by means of which the block 3 is hinged to the base 1, and I also provide a suitable number of hinges 6 by means of which the upper block 5 is hinged 30 to the upper block 3, as shown in Figs. 2 and 3. I also provide a suitable operating handle 35 8 affixed to block 5 for manually operating the device. I also provide suitable means for engaging one edge of the sheet of metal 9, such as a pair of spaced metal plates 10 affixed to the bottom surface of upper block 3 and held in spaced relation by suitable spacing members 12. I also provide a metal plate 13 on the upper surface of base block 1, as shown 40 in Figs. 1 and 2, and a corresponding metal plate 14 on the bottom surface of upper block 5 as shown in Figs. 1 and 2.

In operation the inner edge of the sheet metal plate 9 is inserted between the spaced metal plates 10 and the upper blocks are then 45 swung down to the position shown in Fig. 3 in which position the metal plate 9 is pressed into an approximately semi-cylindrical shape in cross-section, with opposite laterally extending flanges 11, as shown in Fig. 4.

What I claim is—

1. In a device of the class described, an 55 elongated base block having an upstanding approximately semi-cylindrical tapering form, a pair of elongated upper blocks recessed to form a semi-cylindrical tapering recess substantially corresponding with the up- 60 standing form of the base block, one of the upper blocks being hingedly mounted to the base block, a handle attached to the hinged blocks for actuating same, and means carried by one of the blocks for holding the edge of 65 a sheet of metal which is to be pressed into the desired shape to form a mold of the character described.

2. In a machine of the class described, the combination of a base block having an up- 70 standing semi-cylindrical form extending longitudinally of the base block, a pair of upper blocks having a longitudinally extending recess corresponding in shape with the upstanding form of the base block, one of 75 said blocks being hingedly attached to the base block; the said upper blocks being hingedly connected to permit a limited degree of swinging movement relative to each other, means carried by said upper blocks 80 for manually operating same, and means affixed to the innermost upper block to receive the edge of a sheet of metal to be pressed into the desired form to produce the mold.

3. In a machine of the class described, the 85 combination of a base block having an up- standing semi-cylindrical form extending longitudinally of the base block, a pair of upper blocks having a longitudinally extending recess corresponding in shape with the 90 upstanding form of the base block, one of said blocks being hingedly attached to the base block, the said upper blocks being hingedly connected to permit a limited degree of 95 swinging movement relative to each other, means carried by said upper blocks for manually operating same, a pair of metal plates affixed in spaced relation to the lower surface of one of the hinged upper blocks to receive and hold the edge of a sheet of metal while 100 it is being pressed into the desired shape over the form, substantially as shown.

JAY DARLING.
